UNITED STATES PATENT OFFICE.

CLARENCE W. GEYER, OF DONOVAN, ILLINOIS.

END-GATE FASTENER.

1,242,543.

Specification of Letters Patent.

Patented Oct. 9, 1917.

Application filed December 12, 1916. Serial No. 136,483.

To all whom it may concern:

Be it known that I, CLARENCE W. GEYER, a citizen of the United States, residing at Donovan, in the county of Iroquois, State of Illinois, have invented certain new and useful Improvements in End-Gate Fasteners; and I do hereby declare the following to be a full, clear, and exact description of the invention, such as will enable others skilled 10 in the art to which it appertains to make and use the same.

This invention relates to wagons and has special reference to an end gate and fastener therefor adapted to be used to close 15 the rear ends of wagons, the gate being formed of two hinged parts and the fastener being arranged to hold the parts in alinement when in one position and permit their folding in a second position.

One important object of the invention is to improve and simplify the general construction of devices of this character.

A second important object of the invention is to provide an improved end gate and 25 fastener therefor which will have novel means for holding the gate in position and the parts in alinement.

With the above and other objects in view, as will be hereinafter apparent the invention 30 consists in general of certain novel details of construction and combinations of parts hereinafter fully described, illustrated in the accompanying drawing, and specifically claimed.

In the accompanying drawing, like characters of reference indicate like parts in the several views, and:

Figure 1 is a rear view of a wagon with the end gate fastener in its closed position; 40 Fig. 2 is a similar view with the end gate fastener in the open position, one of the rods used herewith being shown in full lines in the position assumed when the two parts of the gate are held in alinement and in 45 dotted lines when the two parts of the gate are permitted to be folded;

Fig. 3 is a plan view of the rear end of a wagon showing the device applied thereto;

Fig. 4 is a section on the line 4—4 of 50 Fig. 3;

Fig. 5 is a section on the line 5—5 of Fig. 1, and

Fig. 6 is a section on the line 6—6 of 55 Fig. 1.

In carrying out the object of this invention there is provided a wagon body having

a bottom 10 and sides 11. On these sides are the spaced guide members 12 which are arranged in pairs on opposite sides of the wagon. Extending through the wagon 60 sides and opening between the guide members of each pair is a vertically elongated slot 13, the outer end of which is protected by a rectangular plate 14 having a suitable opening in its center and provided with a 65 rib 15 extending transversely across the lower end.

The gate itself consists of a major member 16 and a minor member 17 which are connected by means of hinges 18. These 70 members, when in alinement, fit between the guides 12. On the major member is provided a pivot 19 whereon is pivoted a lever 20, the lever being provided on one end with a handle 21. This lever is pivoted 75 intermediate its ends to the pivot 19 and the handle end of the lever works over a ratchet bar 22 wherewith this handle end engages when the fastener is in closed position this construction being clearly shown 80 in Fig. 5.

At 23 are disclosed certain rods, respective ends of the rods being pivoted to the lever 20 on opposite sides of the pivot 19. These rods may either project through the 85 openings 13 as shown in Fig. 1 or may be retracted as shown in Fig. 2. When the rods project through the opening and the handle 21 is swung to the right the hooks 24, which are formed on these rods, will be 90 free from the sides and if now the rods 23 be grasped by the hands it will be seen that said rods may be moved to the position shown in Fig. 2. When the handle 21 is 95 swung to the position shown in Fig. 1 these hooks will engage the ribs 15, the points of the hooks being curved inward of the wagon for this purpose. Thus when the parts are in the position shown in Fig. 1 the outer or free ends of the rods 23 cannot be lifted so as to accidentally slip through the opening and release the gate.

In order to properly guide the bars 23 and to prevent them from falling out of position when retracted as shown in Fig. 2, there is provided on the member 16 the guide 25 through which one of these bars passes, the guide being elongated so that the bar has some freedom of vertical swinging movement. This guide holds this bar 105 in position so that the beveled end 26 of the bar can ride over the lower edge of the slot 110

13 when the bar is projected. On the other member 17 is provided a guide 27 which is open at the top. This guide also holds its bar 23 so that its beveled end 26 can ride 5 over the lower edge of the corresponding slot. However, when the parts are retracted as shown in Fig. 2 then the guide 27, which is open at the top, permits the bar 23 to be raised to the dotted line position shown 10 in that figure. Thus the member 17 is freed from the restraining influence of the bar 23 and may be moved on its hinges. By means of this construction the two members 16 and 17 may be placed in position by simply bending them into angular relation with 15 one another and then inserting the ends between the guides 12 and straightening the two until they come into alinement. When they are in alinement the bar 23 at the right 20 may be dropped into engagement with the guide 27 and the parts manipulated just as though the end gate was a solid board. It is obvious that by reversing this action the board may be removed without raising it 25 vertically.

There has thus been provided a simple and efficient device of the kind described and for the purpose specified.

It is obvious that many minor changes 30 may be made in the form and construction of the invention without departing from the material principles thereof. It is not therefore desired to confine the invention to the exact form herein shown and described but 35 it is wished to include all such as properly come within the scope claimed.

Having thus described the invention, what is claimed is:—

1. An end gate for wagons having sides 40 provided with spaced guides arranged in opposed pairs and having vertically elongated slots opening through the sides between the guides, said end gate comprising major and minor members hingedly connected, and a fastener for said end gate 45 arranged to hold the members in alinement

and in position in the wagon and comprising a lever pivoted intermediate its ends to said major member and having a handle end, a ratchet bar fixed to the major member 50 in the path of the handle end of the lever, rods having respective ends pivotally connected to the lever on opposite sides of its pivot, said rods being projectable through the slots and having hooks on their ends 55 engageable with the sides of the wagon and guides on said gate members receiving said rods, the guide on the minor member being open at the top to permit swinging of its rod free therefrom. 60

2. An end gate for wagons having sides provided with spaced guides arranged in opposed pairs and having vertically elongated slots opening through the sides between the guides, said end gate comprising 65 major and minor members hingedly connected, and a fastener for said end gate arranged to hold the members in alinement and in position in the wagon and comprising a lever pivoted intermediate its ends to 70 said major member and having a handle end, a ratchet bar fixed to the major member in the path of the handle end of the lever, rods having respective ends pivotally connected to the lever on opposite sides of 75 its pivot, said rods being projectable through the slots and having hooks on their ends engageable with the sides of the wagon, guides on said gate members receiving said rods, the guide on the hinged member being open at the top to permit swinging of its rod free therefrom, said hooks having 80 inwardly directed points, and plates on the wagon sides having ribs over which said points engage. 85

In testimony whereof, I affix my signature, in the presence of two witnesses.

CLARENCE W. GEYER.
